US0D1015449S

(12) **United States Design Patent** (10) Patent No.: **US D1,015,449 S**
(45) Date of Patent: ** Feb. 20, 2024

(54) **EXERCISE MACHINE**

(71) Applicant: **TONAL SYSTEMS, INC.**, San Francisco, CA (US)

(72) Inventors: **Robin Barata**, San Francisco, CA (US); **Nina Samarguliani**, Oakland, CA (US); **Daniel K. Harden**, Carmel, CA (US); **Yale F. Shaw**, San Francisco, CA (US); **Ariel D. Turgel**, San Francisco, CA (US)

(73) Assignee: **TONAL SYSTEMS, INC.**, San Francisco, CA (US)

(**) Term: **15 Years**

(21) Appl. No.: **29/820,605**

(22) Filed: **Dec. 22, 2021**

(51) LOC (14) Cl. **21-02**

(52) U.S. Cl.

USPC **D21/662**

CLAIM

The ornamental design for an exercise machine, as shown and described.

DESCRIPTION

FIG. 1 is a front perspective view of a first position of an exercise machine according to an embodiment of our new design;

FIG. 2 is a front elevation view of the exercise machine of FIG. 1;

FIG. 3 is a rear elevation view of the exercise machine of FIG. 1;

FIG. 4 is a right side elevation view of the exercise machine of FIG. 1, the left side being a mirror image thereof;

FIG. 5 is a top plan view of the exercise machine of FIG. 1;

FIG. 6 is a bottom plan view of the exercise machine of FIG. 1;

FIG. 7 is a front perspective view of a second position of an exercise machine, according to an embodiment of our new design;

FIG. 8 is a front elevation view of the exercise machine of FIG. 7;

FIG. 9 is a rear elevation view of the exercise machine of FIG. 7;

FIG. 10 is a right side elevation view of the exercise machine of FIG. 7, the left side being a mirror image thereof;

FIG. 11 is a top plan view of the exercise machine of FIG. 7;

FIG. 12 is a bottom plan view of the exercise machine of FIG. 7;

FIG. 13 is a front perspective view of a third position of an exercise machine, according to an embodiment of our new design;

FIG. 14 is a front elevation view of the exercise machine of FIG. 13;

FIG. 15 is a rear elevation view of the exercise machine of FIG. 13;

FIG. 16 is a right side elevation view of the exercise machine of FIG. 13, the left side being a mirror image thereof;

FIG. 17 is a top plan view of the exercise machine of FIG. 13;

FIG. 18 is a bottom plan view of the exercise machine of FIG. 13;

FIG. 19 is a front perspective view of a fourth position of an exercise machine, according to an embodiment of our new design;

FIG. 20 is a front elevation view of the exercise machine of FIG. 19;

FIG. 21 is a rear elevation view of the exercise machine of FIG. 19;

FIG. 22 is a right side elevation view of the exercise machine of FIG. 19, the left side being a mirror image thereof;

FIG. 23 is a top plan view of the exercise machine of FIG. 19;

FIG. 24 is a bottom plan view of the exercise machine of FIG. 19;

FIG. 25 is a front perspective view of a fifth position of an exercise machine, according to an embodiment of our new design;

FIG. 26 is a front elevation view of the exercise machine of FIG. 25;

FIG. 27 is a rear elevation view of the exercise machine of FIG. 25;

FIG. 28 is a right side elevation view of the exercise machine of FIG. 25, the left side being a mirror image thereof;

FIG. 29 is a top plan view of the exercise machine of FIG. 25;

FIG. 30 is a bottom plan view of the exercise machine of FIG. 25;

FIG. 31 is a front perspective view of a sixth position of an exercise machine, according to an embodiment of our new design;

FIG. 32 is a front elevation view of the exercise machine of FIG. 31;

FIG. 33 is a rear elevation view of the exercise machine of FIG. 31;

FIG. 34 is a right side elevation view of the exercise machine of FIG. 31, the left side being a mirror image thereof;

FIG. 35 is a top plan view of the exercise machine of FIG. 31; and,

FIG. 36 is a bottom plan view of the exercise machine of FIG. 31.

The broken lines shown in the drawings are for purposes of illustrating portions of the exercise machine that form no part of the claimed design.
